UNITED STATES PATENT OFFICE.

CONRADIN ALFRED BREITUNG, OF SEATTLE, WASHINGTON.

INTERNAL-EXPLOSION ENGINE.

1,147,370.

Specification of Letters Patent.

Patented July 20, 1915.

Application filed January 19, 1914, Serial No. 813,124. Renewed November 27, 1914. Serial No. 874,353.

To all whom it may concern:

Be it known that I, CONRADIN ALFRED BREITUNG, a citizen of the United States, and resident of Seattle, King county, Washington, have invented certain new and useful Improvements in Internal-Explosion Engines, of which the following is a specification.

My invention relates to internal explosion engines and comprises certain novel constructions and combinations of parts which will be hereinafter described and particularly pointed out in the claims.

The objects of my invention are to improve the effectiveness of the apparatus as a generator of power and particularly along the line of a higher compression of the charge and the apparatus by which this is accomplished.

In the accompanying drawings I have shown my invention in the form which is now preferred by me.

Figure 1 is a sectional elevation taken on the axial plane. Fig. 2 is a plan view of the engine. Fig. 3 is a transverse sectional elevation taken through the impact wheel which forms the main rotor and through the final charge-compression cylinder. Fig. 4 is a transverse sectional elevation taken through the chamber which contains the primary air-compressing rotor. Fig. 5 is a fragmentary section showing the emergency or relief valve which communicates with the charge-compressing cylinder. Fig. 6 is an end elevation. Fig. 7 is a longitudinal section through the water injecting valve. Fig. 8 is a transverse section through the water injection valve.

My engine contains as its principal parts, a main rotor or power producing member by which the other parts are turned, a primary air compressing rotor turned by the main rotor and which gives the air a preliminary and relatively slight compression, and a final air compression piston, the chamber of which is also employed as an explosion or combustion chamber, from which the products of combustion are discharged upon the main or power developing rotor.

The main rotor 1 is herein shown as an impact wheel mounted upon the shaft 10. This rotor, as shown, has its periphery provided with a large number of pockets 11, into which the products of combustion are discharged from the combustion chamber 2 through a port 12, which is controlled by a

rotary valve 13. The direction of turning of this rotor is shown by the arrow in Fig. 3. That part of the peripheral inner wall of the chamber in which this rotor turns, which it passes before reaching the port 12, is for a considerable distance, a close fit to the periphery of the rotor 1. Almost immediately after leaving the port 12, the inner peripheral wall of this chamber gradually separates or is removed from closeness to the periphery of the rotor, thus forming a discharge channel 14 of rapidly enlarging section, which will freely convey the gases to the discharge opening 15.

Secured to a continuation of the shaft 10, is the primary air compression mechanism, which is shown in Fig. 4. This should be of a rotative character, as it is to be operated by direct connection with the rotor 1. As shown it employs a chamber 3 which is circular in outline but eccentric to the shaft. Upon the shaft is a head 30 which has a slot extending therethrough transversely of the shaft, in which slot a piston blade 31 reciprocates, also transversely of the shaft.

The ends, or heads, of the chamber 3 have each a circular groove 35, extending to the periphery, in which rollers 36 travel, these rollers being journaled upon an edge of the piston plate 31, whereby this edge of plate 31 is kept in close contact with the periphery of the chamber. The air inlet for this chamber is at 32 and the outlet through the port 33. A gate 4 is pivoted at 40 and may swing inward so as to rest upon the curved cam-like surfaces 37 of the head 30, or outward until seated in the recess 34. The curved surface 38 of the piston blade 31, also acts as a cam surface in combination with the cam surface 37, to assist in moving this gate outward.

In operation, the air entering through port 32 is swept around by the piston plate 31, compressed and driven out through the port 33, the gate 4 maintaining its swinging end in contact with either the head 30 or the piston blade 31 and preventing the air being driven out through the port 32. The port 33 conducts the air to the final compression chamber 2. I have shown this of rectangular shape, although this may be round. Within this chamber is a piston 20, to which is attached a bar 21 having teeth thereon meshing with those of a gear 22 secured on a shaft 23. This gear may be only a fractional gear, as its duty is to reciprocate the

2
piston 20. I have provided a roller 24, bearing against the back side of the rack bar 21 to hold it in mesh with the gear.

The main shaft 10, outside the case, has a 5 partial or interrupted gear 16 secured thereto, its teeth meshing with those of a pinion 17, to which is secured a crank arm 18 which is connected by a link 19 with a crank arm 25 secured to a shaft 23; to which the pinion 22 is also secured. Crank arm 18 is shorter than that crank arm 25 to which it is connected by link 19, so that a complete revolution of wheel 17 will cause a to-and-fro 10 oscillation of arm 25 and of the wheel 22 which is secured thereto through the shaft 15 20 25 which is secured thereto through the shaft 23. The partial gear 16 is proportioned to 20 the time of turning of wheel 16. The port 33, which connects the primary compression chamber 3 with the final compression and combustion chamber 2, is controlled by a sliding or gate valve 5 which is attached to 25 one end of a pivoted lever 51 by a stem 50. The lever 51 is rocked by a crank 52 which is secured to one end of a shaft 53. To the other end of the shaft 53 is secured a tappet or cam lever 54 which is in position where 30 it is engaged and controlled by the end of the crank arm 18. A spring 56, acts upon the tappet lever 54 to draw its end down, which acts to close the valve 5. This occurs 35 at the beginning of the forward movement of the piston 20 and the valve remains closed until after the piston begins its return movement, that is, until arm 18 has passed into contact with the lever 54 toward the completion of its rotation, when it rocks the 40 arm 54 so as to open the valve. A rocking valve 13 lies in and controls the port 12 which connects the chamber 2 with the main rotor 1. The protruding stem of this valve is shown at 47 in Fig. 6. To this stem is 45 secured a crank arm or lever 46 which is connected by a link 45 with a lever 41, which is pivoted at 40 adjacent the pivot of the arm 25. The arm 41 has two fingers 42 and 43 and arm 25 has two fingers 26 and 27, which 50 engage as the arm 25 rocks, thereby rocking the lever 41. The forward movement of the lever arm 25, is well advanced before the finger 26 engages the finger 43, which starts the lever 41. This movement is enough to 55 swing the lever 46 through an arc which is indicated by dotted lines in Fig. 6. The lever 46 has a tooth or projection 48 which contacts with one end of a pivoted lever 57 which controls a valve 6, see Figs. 3, 7 and 8, 60 by which a momentary injection of cooling water is secured. This valve has a central bore 60 and a lateral bore 61 connecting therewith and adapted to communicate with a source of water supply under pressure, as 65 the space 62, which might be the cooling

jacket. The combustible fluid or gas is injected through the pipe 7 into the compressed air. Spark plugs 8 are provided for igniting the charge. The means for controlling the action of these two mechanisms are not shown. They may be anything which is found suitable and desired. A charge having been compressed within the chamber 2 and ignited, the valve is opened to discharge the gases upon the buckets or 70 vanes 11 of the wheel 1, turning this. The primary air compressor forces a charge of air into chamber 2 while the piston 20 is drawn back. The engagement of the interrupted gear 16 with pinion 17 starts the 75 levers which operate the valves and also advances piston 20, thus completing the cycle. The time at which ignition occurs in the chamber 2 is before the piston 20 reaches the end of its compression stroke, say at 80 about 75% of the length of stroke. The full stroke should continue until the face of the piston approaches as close to the end wall of the chamber as is found practicable. I provide a valve 9 which controls a passage 85 leading direct from the chamber 2 to the exterior, which may be used as a manually controlled relief valve. This valve opens against the pressure in the chamber and thus will open to admit air from the exterior at 90 the beginning of the return stroke of the piston 20, or until communication is re-established with the primary compression chamber 3. Externally the stem of this valve is engaged by a lever 90, by which 95 the valve may be held off its seat, so that the compressed charge of air may be liberated, in part or wholly, should this be desired. The valve is normally held continuously against its seat by a spring 91. 100 What I claim as my invention and desire to patent is:

1. In an engine, in combination, a main or power developing rotor, a preliminary air-compressing chamber and a rotor therein connected to and rotating with the main rotor, a final-compression cylinder and a piston therein operated from the main rotor, a valve between said cylinder and the preliminary air-compressing chamber, a valve between said cylinder and the main rotor, and means for operating said valves from the main rotor.

2. In an engine, in combination, a main rotor, of impact type, an explosion chamber having a discharge port leading to the main rotor, a valve controlling said port, a piston in the explosion chamber, means for intermittent reciprocation of said piston actuated from the main rotor, means for injecting the combustible into the explosion chamber and separate air-compressing means actuated from the main rotor for supplying the air to said explosion chamber.

3. In an internal combustion engine, a

- main or power rotor, a preliminary air compression mechanism, a combustion chamber communicating by a port with the main rotor, a valve controlling said port, a compression piston reciprocable in said chamber, a port connecting the compression chamber with the preliminary air compression mechanism, a valve controlling said port, a partial or segment gear turning with the main 5 rotor, a pinion engaged by and given one complete turn by said segment gear, and mechanism operated from said pinion for controlling said valves and the air compressing piston.
- 15 4. In an internal combustion engine, a main or power rotor, a preliminary air compression mechanism, a combustion chamber communicating by a port with the main rotor, a valve controlling said port, a compression piston reciprocable in said chamber, a port connecting the compression chamber with the preliminary air compression mechanism, a valve controlling said port, a partial or segment gear turning with the main 10 rotor, a pinion engaged by and given one complete turn by said segment gear, a crank turned by said pinion, a rock shaft having a crank thereon of greater length than that connected with the pinion, a link connecting said cranks, and means for actuating the air compressing piston and the valves from said rock shaft.
- 15 5. In an internal combustion engine, a rotative power generating mechanism, a combustion chamber separate from but having a port connection with said power generating mechanism, a piston reciprocable in said combustion chamber to compress the charge therein, a piston rod therefor having teeth thereon constituting a rack, a pinion engaging said rack, a segment gear rotated by the power generating mechanism, a pinion rotated by said segment gear once for each turn of the latter, and a power transmitting mechanism connecting said latter pinion with the one which engages the teeth on the piston rod, said power transmitting mechanism containing parts which convert the rotation of one pinion into an oscillation of the other.
6. In an internal combustion engine, a
- rotative power generating mechanism, a combustion chamber separate from but having a port connection with said power generating mechanism, a piston reciprocable in 55 said combustion chamber to compress the charge therein, a piston rod therefor having teeth thereon constituting a rack, a pinion engaging said rack, a segment gear rotated by the power generating mechanism, 60 a pinion rotated by said segment gear once for each turn of the latter, and a power transmitting mechanism connecting said latter pinion with the one which engages the teeth on the piston rod, a crank rotated by 65 the piston which engages the segment gear, a crank of longer radius connected with the pinion which engages the rack on the piston rod, and a link connecting said cranks.
7. In an internal combustion engine, in 70 combination, a main or power generating rotor, an igniting chamber having a discharge connection with said rotor, a cylindrical air compressing chamber alongside the rotor and having its axis offset from and 75 parallel to the axis of the rotor, a head within said compressing chamber and secured to rotate with the main rotor, said head having a guide channel extending transversely through it and of an axial 80 length corresponding with the length of the compression chamber, a piston plate mounted to reciprocate in said channel transversely of the shaft, means maintaining one end of said piston plate in continuous contact with 85 the periphery of the compression chamber, a section of said peripheral wall being hinged to form a gate adapted to swing inward, the swinging end of said gate extending toward the advancing piston plate, the head 90 and one end of the piston plate being curved to form a lifting cam for said gate, a port back of said gate communicating with the ignition chamber, and a valve controlling 95 said port.

In testimony whereof I have hereunto affixed my signature this 14th day of January, 1914.
